SIPHON ADAPTER FOR BOTTLES

Earl E. Sousley, Upper Darby, Pa.

Application November 2, 1931; Serial No. 572,703

Renewed December 4, 1933

2 Claims. (Cl. 215—5)

This invention relates to devices for removing the contents, as required, from containers, such as bottles, having various depths and necks of various circumferences.

5 The primary object of the invention is to provide an adapter of this kind which may be placed over the mouth and neck of containers, containing carbonated or charged liquid or a liquid giving off a gas, and which will draw off the liquid and not permit the escape of gas no matter if the containers vary as to their depth or the circumference of neck.

Another object is to provide a device of this kind particularly adapted for use with ordinary 15 bottles containing carbonated drinks, which device may be adjusted to close off the mouth of the bottle and which will adjust itself to reach the bottom of the bottle so that the contents of the bottle will be prevented from escaping except 20 when desired.

Still another object of this invention is to provide an adapter of this kind, the stem of which may be inserted in a container and extended or retracted to reach various depths thereof, including the bottom.

Another object is to provide a telescoping stem in an adapter of this kind which stem when telescoped or extended may be inserted or withdrawn from containers of various depths without disturbing the adjusted length of the stem.

Another object is to provide an adapter of this kind which includes a detachable telescoping tubing for insertion into the bottle or other container, so that the same may be replaced if desired without discarding a relatively more expensive valve portion of the adapter.

Other objects and advantages of the invention will be apparent during the course of the following detailed description, taken in connection with the accompanying drawing, forming a part of this specification and in which drawing:

Figure 1 is a vertical sectional view of the improved adapter clamped in place on an ordinary carbonated drink bottle.

45 Figure 2 is a view partly in section on the line 2—2 of Figure 1.

Figure 3 is a view substantially on the line 3—3 of Figure 2.

Referring to the drawing in detail, and wherein 50 similar reference characters designate corresponding parts thruout the several views, the letter A designates an ordinary carbonated liquid bottle and B the improved adapter therefor.

Referring first to the container or bottle A, the 55 same includes a mouth 5, a neck 6, a shoulder or

flange 7 on the exterior of the neck and a bottom 8.

As for the improved adapter, the same includes a valve housing portion 10 with an upperstanding tubular portion 11 at its upper end, 60 having a flange or finger hold 12. The uppermost or free end of the tubular portion 11 forms an abutment 13 while the lower end of the tubular portion, where it joins the valve housing portion 10, is provided with a spring seat 14 65 thru the center of which is a valve stem way 15. This way opens into a substantially circular passageway 16 from which an elongated spout or outlet 17 outwardly and downwardly curved, leads for the discharge of the contents of the bottle. 70 At the lower end of the passageway 16 is a valve seat 18 which comprises a downwardly extending flange about the lower end of the passageway. This flanged seat 18 is enclosed by the walls of a circular recess 19, the walls being spaced from 75 the seat. The walls of this recess 19 may be provided with grooves or threads 20, the purpose of which will be later described. The recess 19 opens into a washer seat 21. From the lower end of the valve housing portion 10 extends a 80 bell-shaped skirt portion 22, the interior circumference of which will be slightly larger than the outer circumference of the shoulder 7 of the bottle A and preferably extend below the shoulder as shown in Figure 1. Oppositely positioned slots 85 23 are preferably cut into the lower end of the skirt portion 22 from the side walls of which are outwardly projecting ears 24. These slots 23 and ears 24 may be formed by making a T-shaped cut into the skirt portion and bending outwardly 90 the two portions formed by the cut. Pivots connected to the ears 24 by pivot pins 25 or the like are levers 26 which are preferably knurled or grooved as at 27 and cams 28 which form a continuation of the levers 26 and which extend 95 thru the slots 23 and are shaped to directly engage the lower portion of the shoulder 7 of the bottle A as shown in Figure 3.

A valve 30 is provided having a downwardly projecting dome-like free end which projects into 100 the recess 19, and also having a recess 31 at its opposite end in which a washer 32 suitably secured in the recess. The walls of this recess 19 encircle the flange of the valve seat 18 when the valve is seated. A valve stem 33 extends from the 105 valve 30 upwardly thru the passageway 16, way 15 and tubular portion 11, where it is secured, as by screw threading to a button 34 or the like crowning the tubular portion and also extending a short distance within the same. Formed on the 110

- button 34 is a shoulder 35 which abuts the abutment 13 when the button is depressed and prevents further movement of the button. This movement may however, be regulated, by partly screwing or unscrewing the button 34 from the valve stem 33 and therefore decreasing or increasing the extent to which the valve may move away from its seat. Encircling the valve stem is a coil spring 36 with one of its ends bearing against the lower portion of the button 34 and the other against the spring seat 14. This spring 36, of course, forces the valve to seat and also forces the button away from the upper end of the tubular portion.
- 15 A bottle-mouth-engaging washer 37 of rubber or the like and of sufficient body to provide for considerable compression is carried in the washer seat 21. The diameter of the opening in the washer is preferably less than the diameter of the 20 smallest mouth of any bottle on which the device is employed. It is preferred that this opening in the washer be beveled and that the outer edge of the washer also be beveled and extend to engage the walls of the recess.
- 25 Loosely encircling the skirt portion 22 is a ring 38 of heavy wire or the like having oppositely disposed ears 39 as shown in Figure 2 extending outwardly from the ring. It is preferred that the cross sectional area of the ring be circular as 30 shown in Figure 3. These ears 39 engage the grooves or knurls 27 on the face of the levers 26 when the cams are in engagement with the shoulder of a bottle and prevent the levers from springing up and disengaging the cams.
- 35 Extending downwardly from the valve housing portion 10 and to the skirt portion 22 is an elongated upper tube 40 shaped somewhat like the ordinary funnel or thistle tubes, having a shank 41 and a funnel or cup portion 42 at one end of 40 the shank. On the upper outer end of this cup portion 42 are lugs or threads 43 which engage the grooves or screw threads 20 of the valve housing. Of course, the lugs may be placed on the valve housing and the grooves in the cup portion 45 42 of the tube 40, since either way the tube 40 may be detachably secured to the valve housing with the open end of the cup portion 42 encircling the dome-shaped valve 30 and providing for space for the latter when depressed. The opposite end of the tube 40 is flared or flanged as at 44.
- An elongated lower tube 45 preferably telescopes within the upper tube 40 while the latter is of a length to extend about half way down into 55 an average size carbonated liquid bottle. The lower tube 45 is of a length sufficient to be extended or telescoped from the tube 40 to the bottom of bottles of different depths. The bottom end of the tube 45 is preferably beveled as 60 shown at 46 in Figure 1 so that, if the tube abuts the bottom 8 of a bottle, as shown in Figure 1, the bevel will prevent the bottom from closing off the inlet to the tube.
- Secured to the free end of the tube 40 is a retaining sleeve 47 of rubber or the like, which is held upon the tube 40 by the flange 44 and the inner surface of the walls of which engage the outer surface of the walls of the tube 40 as well as the outer surface of the walls of the tube 45. 70 Thus the sleeve serves two purposes. It prevents gas and fluid from flowing thru the space between the two tubes and also holds the two tubes adjustably telescoped. Of course two or more

tubes may be substituted for the tube 45 with two or more sleeves 47. Both the upper and lower tubes are preferably of glass while the rest of the device with the exception of the washers 32 and 37 and sleeve 47 is preferably of metal. The washers and sleeve are preferably of rubber or the like.

In use, the adapter may be placed over the open mouth of any container provided with a shouldered neck. When so placed the washer 32 contacts with the mouth of the bottle. By depressing the levers 26 the cams 28 will engage the lower portion of the shoulder 7 of the bottle A and at the same time the ring 38 will slide downwardly until the ears 39 of the ring 38 engage a groove on each lever from which they cannot move any farther. This cam and leverage action will compress the washer 32 tightly against the washer seat 21 and the mouth 5 of the bottle, thus preventing the escape of gas and liquid from around the edge of the mouth. Since the ring 38 is spaced from the skirt 22, it will be seen that the skirt is not forced against the shoulder or neck of the bottle, and from Figure 3 it will be seen that the cam itself engages the shoulder of the bottle and not the skirt portion of the adapter.

As for the tube, if the lower tube is initially extended before inserting into the bottle, it will telescope within the upper tube just enough when inserted into the bottle so that the bottom of the lower tube will abut the bottom of the bottle. When the device is withdrawn from an empty bottle, the sleeve 47 will prevent the lower tube from dropping out of the upper tube.

When the button 34 is depressed the valve will 110 unseat and permit the flow of liquid past the valve seat, into the passageway 16 and out of the outlet 17.

When removing the adapter from a bottle, all that is necessary is to pull up on the levers enough 115 to force the ears of the ring out of the grooves or knurls and the cams out of engagement with the shoulder of the bottle.

Changes in detail may be made to the form of invention herein shown and described, without 120 departing from the spirit of the invention or the scope of the following claims.

What is claimed is:

1. In a bottle siphoning device adapted for use on containers having an open mouth and a shouldered neck, a valve, a valve housing, a skirt portion extending from the lower end of the valve housing, a ring about the skirt portion and wholly spaced therefrom, and a shoulder engaging cam pivoted to the skirt portion, having an outwardly extending lever provided with grooves, the inner periphery of said ring engaging the lever in said groove when the cam engages the shoulder preventing movement of the cam away from the shoulder.

2. In a bottle siphoning device adapted for use on containers having an open mouth and a shouldered neck, a valve, a valve housing, a skirt portion extending from the lower end of the valve housing, a shoulder engaging cam pivoted to the skirt portion having an outwardly extending lever provided with grooves, and a ring about said skirt portion and spaced therefrom having an ear engaging the grooved portion of said lever when said cam engages the shoulder, preventing movement of said cam away from said shoulder.

EARL E. SOUSLEY.
